UNITED STATES PATENT OFFICE.

BENJAMIN F. CALDWELL, OF POMONA, CALIFORNIA.

FURNACE.

Application filed August 9, 1921. Serial No. 490,990.

To all whom it may concern:

Be it known that I, BENJAMIN F. CALDWELL, a citizen of the United States, residing at Pomona, in the county of Los Angeles 5 and State of California, have invented a new and useful Furnace, of which the following is a specification.

This invention relates to furnaces designed primarily to be used in rooms where 10 there are no spaces under the floors in which to hang floor furnaces, the said furnace thus being designed primarily for use on the upper floors of buildings where a furnace hanging in the floor would give an unsightly 15 appearance to the room therebelow. The furnace is also to be used where there is a concrete floor near the ground so that it is rendered convenient and advisable to place the furnace above the floor level.

20 Another object is to provide a furnace designed to take the place of a radiator or a stove such as often used in a room, the present device, however, having the additional advantage of providing fresh warmed air 25 to the room and avoiding the unhealthy process of heating used, devitalized or foul air, the furnace also serving to keep all products of combustion out of the room so that there is no danger such as results 30 from the escape of gases into a room.

Another object is to simplify and otherwise improve upon the construction of furnace disclosed for example in my co-pending application No. 452,022 filed March 14, 35 1921, thereby to adapt it for the purposes hereinbefore mentioned.

With the foregoing and other objects in view which will appear as the description proceeds, the invention resides in the combination and arrangement of parts and in the details of construction hereinafter described and claimed, it being understood that, within the scope of what is claimed, changes in the precise embodiment of the invention shown can be made without departing 45 from the spirit of the invention.

In the accompanying drawings the preferred forms of the invention have been shown.

50 In said drawings

Figure 1 is a view partly in side elevation and partly in section of a furnace embodying the present improvements.

55 Figure 2 is a section on line 2—2, Figure 1.

Figure 3 is a section on line 3—3, Figure 1.

Figure 4 is a transverse section through the base portion of a furnace having an air inlet through the floor thereunder.

Referring to the figures by characters of reference 1 designates the outer casing of the furnace which can be of any desired contour and proportions, this casing resting on the floor F and being provided in its walls 65 at the lower ends thereof with air inlet openings 2 covered with suitable screens or grills 3. The top of the casing, which is indicated at 4, has a plurality of air outlets 5.

70 Mounted within the lower portion of the casing and spaced from the walls thereof is an elongated housing 6 provided with inwardly extending flanges 6' supporting a plate 7 having an opening 8 in one end portion thereof. A box 8' having an open end, is inserted into one end of the casing 1 and housing 6. This box supplies fresh air to the opening 8. In this opening is seated the lower end of a combustion tube 9 in which is supported a burner 10 to which fuel is supplied through a pipe 11 extending into the box 8'. A radiator 12 is mounted on the plate 7 and extends around and above the combustion tube but terminates below the top 4 of the casing. This radiator has a top plate 13 and mounted in the top plate are the upper ends of air flues 14 the lower ends of which engage the plate 7.

75 Similar radiators 15 are mounted at intervals on the plate 7, each containing air flues 16 extending longitudinally therethrough and the several radiators are connected near their upper and lower ends by gas flues 17. An outlet flue 18 extends from the last radiator of the group and through the adjacent wall of the casing 1 and constitutes an outlet for the spent products of combustion, it being understood that this outlet flue can be extended through a wall of the room or 80 into an outlet pipe or stack.

85 Those portions of the plate 7 between the radiators are provided with small openings 19 whereby fresh air can flow upwardly from the interior of the housing 6 and between the radiators.

90 In the structure shown in Figure 3 an air flue 20 extends through one of the walls W of the room and through one wall of the casing 1 and of the housing 6, this flue open- 100

ing into the housing close to and under the combustion tube 9. A damper 21 is pivotally mounted in the upper portion of the flue and has a weight 22 thereon for holding 5 the damper normally closed or in an inclined position across the flue. A cross strip 23 is mounted within the housing 6 and has a longitudinal slot 24 in which a pin 25 is slidably mounted. A link 26 connects this 10 pin with the damper. Another link 27 extends downwardly from the pin and is attached to one end of a chain 28 or other flexible element extending under and upwardly from a guide sheave 29 mounted on 15 the housing 6. A rod 30 may be attached to this chain and is preferably extended through the top 4 of the casing 1, it being understood that this rod can be supported in elevated position by any suitable means 20 provided for that purpose.

When fuel is ignited at the burner 10 the combustion will be supported by fresh air entering box 8' and the hot products of combustion will raise the temperature of the 25 tube 9 to a high degree and said products of combustion will then flow around the tubes 14 so as to heat them and also heat the radiator 12. Said products will then flow through the flues 17 and heat them and then 30 pass successively into the other radiators which, with their flues 16, will be thoroughly heated. Thus air entering the openings 2 will circulate between the casing 1 and the housing 6 and between the radiators and 35 will pass outwardly through the openings 5. At the same time a certain amount of air from the outside will enter the housing 6 by way of flue 20. This air will flow upwardly through the flues 14 and the openings 19 40 and thus be thoroughly heated. Obviously by manipulating the damper 21 the amount of air admitted to the housing 6 can be regulated and the heating of the room can thus be controlled.

45 Instead of having fresh air admitted to the housing 6 through one of its side walls an opening 31 can be provided in the floor F where possible and as shown in Figure 4. Under these conditions a weighted damper 50 32 is pivotally mounted on the floor and is connected directly by a chain 33 to a damper

34 which, in turn, is connected by a chain 35 to the actuating rod 36. Thus when damper 32 is closed the damper 34 is automatically opened so that air from the room can be 55 heated.

The number of radiators employed can be varied according to the cubic area of the room to be heated.

What is claimed is:—

60 1. A furnace including a casing having an air inlet and an air outlet adjacent the bottom and top thereof respectively, a housing within and spaced from the walls of the casing, a combustion tube extending upwardly from the housing, a fresh air box projecting into the housing and opening into the combustion tube, a burner supported within the combustion tube, radiators mounted on the housing and within and spaced from the casing, one of said radiators enclosing the combustion tube, air flues extending through the radiators and communicating with the housing, and means for directing fresh air into the housing in controllable quantities. 70

75 2. A furnace including a casing having an air inlet and an air outlet adjacent the bottom and top thereof respectively, a housing within and spaced from the walls of the casing, a combustion tube extending upwardly from the housing, a fresh air box projecting into the housing and opening into the combustion tube, a burner supported within the combustion tube, radiators mounted on the housing and within and spaced from the casing, one of said radiators enclosing the combustion tube, air flues extending through the radiators and communicating with the housing, means for directing fresh air into the housing in controllable quantities, and flues connecting the upper and lower portions of the radiators, there being air outlets in the top of the housing and opening between the radiators. 80

85 In testimony that I claim the foregoing 90 as my own, I have hereto affixed my signature in the presence of two witnesses.

95 BENJAMIN F. CALDWELL.
